UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

APPARATUS FOR USE IN THE MANUFACTURE OF SHOES

Application filed August 17, 1925. Serial No. 50,643.

This invention relates to apparatus for use in preparing shoe materials for operations such, for example, as pulling-over or lasting, or for presenting the work to the operator of a machine for performing such operations. The invention is herein illustrated as embodied in apparatus particularly designed for use in connection with a machine for lasting tennis shoes to facilitate the assembling 10 of the upper materials on the lasts, to pull the uppers forwardly on the lasts, and to present the work in convenient position for the operator of the lasting machine to receive it and present it to that machine. In various novel 15 and useful aspects, however, the invention is not limited to tennis shoe work, nor is it limited to apparatus including the several features herein shown in combination.

In the treatment of upper materials to position them in proper relation to the last or otherwise to prepare them for pulling-over or lasting operations, it is preferable that the work be positioned with the last bottom downward so that the workman may have the 25 top of the forepart of the upper conveniently in view and may thus be enabled to determine readily when the lines of the upper are in proper relation to the contour of the last. It is a common practice, for example, to pull 30 the upper forwardly on its last by the use of a gripper of the type illustrated in Letters Patent No. 1,139,613, granted on May 18, 1915, upon an application of P. J. Wentworth, the last being positioned bottom downward and tipped relatively to the gripper to cause the gripper to pull the upper. Where 35 the work is subsequently to be presented bottom upward to a shoe machine, for example to a lasting machine of the bed type, it is more convenient for the operator of such a machine if he receives it bottom upward, since he may thus more readily grasp it in such manner as to hold the upper in proper 40 position on the last during the presentation 45 of the work to the machine. The present invention, in one important aspect, accordingly provides novel means for presenting the work to the operator of a shoe machine, whereby the work is moved to bring it into the best 50 position for the operator to receive or grasp

it. In the construction herein illustrated as an embodiment of this feature of the invention an upper-pulling device of the same general type as that shown in the above-mentioned Wentworth patent is mounted for turning movement with the work from a position in which the last is bottom downward to a position in which it is bottom upward. After the upper has been properly pulled, the operator is thus enabled, while the upper is still under tension, to place his hands on the work in positions which are most convenient and effective for holding the upper properly positioned on the last during the transfer of the work, still bottom upward, to the lasting machine. The construction shown further provides means for holding the work with the upper under tension until the operator is ready to receive it.

In another important aspect the invention provides improved means for pulling an upper forwardly on the last. The construction shown comprises a gripper having pairs of jaws which are spaced apart laterally of the shoe so as to engage the upper substantially at the corners of the toe, and relatively to which the last is tipped to pull the upper. The pull is thus applied to the upper along the opposite sides of the last in such manner that the entire forepart of the upper is subjected to a forward pull to draw the upper tightly about the heel end of the last and to take up the slack in the shank without danger of applying an undue excess of pulling force in any location, for example along the median line of the upper, such as might tend to "bow" the tip seam where shoes are provided with tips. A further advantage in the use of the construction shown, with the gripper jaws engaging the upper at the corners of the toe, is that the upper is pulled over the toe end of the last in such manner as to reveal to the operator the contour of substantially the entire toe of the last, and thus enable him readily to judge whether the lines of the upper are in proper relation to the lines of the last. In the use of a gripper such as herein shown the operator is, moreover, enabled, by swinging the heel end of the last laterally, to effect readily the proper relative adjustment

of the upper and the last, since the gripper holds the entire toe end of the upper from shifting as the last is swung to bring it into the correct angular relation to the upper.

It is a further object of the invention to relieve the operator of a shoe machine such, for example, as a lasting machine of the type above-mentioned, of the necessity of preparing the work for presentation to the machine, thus providing for a substantial increase in the production of the machine, with resulting economies. The invention accordingly further provides a construction whereby the last and its shoe materials are carried from a location where a different operative performs the preparatory work thereon to a location convenient for the operator of the machine to receive them. The construction shown comprises a rotatable carrier or turret having mounted thereon a plurality of work-presenting devices comprising grippers of the character hereinabove described, by the use of which the uppers are preliminarily tensioned and adjusted on the lasts and are then carried while under tension to the operator of the lasting machine, the lasts with their shoe materials being automatically inverted, as the turret is turned, to present them bottom upward.

The various features of the invention will now be more particularly described by reference to the accompanying drawings and thereafter pointed out in the claims.

In the drawings

Fig. 1 is a view partly in side elevation and partly in vertical section of apparatus in which the invention is embodied;

Fig. 2 is a view on a larger scale of a portion of the structure shown at the right-hand side of Fig. 1, showing in greater detail one of the work-presenting devices;

Fig. 3 is a view on a larger scale of a portion of the structure shown at the left-hand side of Fig. 1, illustrating how the work is inverted;

Fig. 4 is a plan view of the structure shown in Fig. 2;

Fig. 5 is a section on the line 5—5 of Fig. 3, and

Fig. 6 is a view of a portion of the work-holding means with parts in section on the line 6—6 of Fig. 2.

The apparatus comprises a base 2 which may rest on the floor, and a vertical spindle 4 secured to said base and provided with a plurality of laterally projecting pins or arms 6 adapted to hold a supply of shoe uppers in convenient positions for a workman to reach them. Mounted for turning movement about the spindle 4 is a turret 8 which is shaped like a bowl to hold a supply of lasts on which the uppers carried by the pins 6 are to be mounted. Arranged about the periphery of the turret 8 to turn therewith are a plurality of work-presenting devices, hereinafter more particu-

larly described, in which the workman positions the lasts and uppers after mounting the uppers on the lasts. The workman stands at one side of the apparatus adjacent to a table 10 which is fast on the spindle 4 and upon which the last may be supported as the upper is mounted thereon. The workman turns the turret 8 manually as he positions the lasts and uppers in the different work-presenting devices, and in this manner the assembled lasts and uppers are carried around to a different location where the operator of a shoe machine, for example a lasting machine, receives them and presents them to the machine.

Each of the work-presenting devices comprises a shaft 12 which is mounted horizontally to turn in a bearing formed in the edge of the turret 8 and has fast thereon a bracket 14 to which is secured by a screw 16 a member 18 having integral therewith a pair of lower gripper jaws 20. Co-operating with the jaws 20 are a pair of upper gripper jaws 22 which are rigidly connected together and are mounted to turn about a pivot stud 24 on the member 18. Formed integral with the movable jaws 22 is a forwardly extending arm 26 upon which is adjustably mounted a shoe rest member 28. A light spring 30 holds the jaws 22 normally spaced from the jaws 20 so that the margin of the toe end of an upper may be readily inserted between the jaws. After the upper has been thus inserted, the workman presses the last downwardly upon the rest 28 and by such pressure closes the jaws upon the upper, and then by tipping the last about the rest member 28 the workman causes the jaws to pull the upper forwardly on the last while they are held closed on the upper.

Pivottally mounted upon a stud 32 on a lug 34 which is fast on one end of the pivot stud 24 is a lever 36 the outer end of which is shaped to provide a handle, and projecting laterally from this lever is an arm 38 which is curved as shown in Fig. 6 to extend over the top or instep portion of the last. The stud 24 is mounted to turn in bearings in the member 18 and has thereon a spring 40 which tends to turn it in the direction to swing the lever 36 downwardly as the parts are positioned in Fig. 2. The arm 38, under the force of the spring 40, is thus adapted to hold the last tipped about the rest member 28 so as to maintain the upper under forward tension. A projection 42 on the lug 34 serves by engagement with a projection 44 on the bracket 14 to limit swinging movement of the lever 36 under the influence of the spring 40 in the absence of any work. When a last with its upper has been presented to the gripper and the upper has been pulled forwardly by tipping the last about the member 28, as above described, the operator raises the lever 36, after swinging it laterally about its

5 pivot 32 far enough for the arm 38 to clear the shoe as it is moved upwardly, and thereafter swings it to carry the arm 38 over the shoe and then releases it to the action of the spring 40. The arm 38 will thus hold the last tipped about the member 28 with the upper under forward tension until such time as the operator of the lasting machine is ready to take the work and present it to that machine.

10 To prevent undesirable idle swinging movement of the lever 36 about its pivot stud 32 there is provided a spring 46 which encircles the stud and acts on the lever to hold it normally in the position determined by 15 shoulders formed on the lever and on the bracket 14 respectively and abutting at 48, as indicated in Fig. 4. In this position of the lever the arm 38 is below the position occupied by the shoe, and since the stop 44 is so arranged as to prevent the lever from being 20 swung downwardly far enough to be out of convenient reach of the operator, it may happen that the arm 38 will sometimes be engaged by the work when the last is tipped to 25 effect the pulling of the upper. In order that the workman may not have to swing the lever 36 to carry the arm 38 away from the path of the shoe before the upper is pulled, the arm 38 is pivotally mounted at 50 (Fig. 6) on the 30 lever 36 so that it may be swung downwardly if engaged by the work. A spring plunger 52 which engages a finger 54 on the arm 38 opposes comparatively light resistance to 35 swinging movement of the arm and serves to hold the arm normally in a position determined by engagement of a shoulder 56 thereon with the side of the lever 36.

40 Each of the work-presenting devices, by movement of its shaft 12 in the bearing in the turret 8, may be turned from a position in which the last is bottom downward, as shown in Fig. 2, to a position in which the last is presented bottom upward, as shown in Fig. 3. In the construction shown such 45 turning movement to change the position of the work is effected as an incident to the turning of the turret 8 about its vertical axis. As shown in Fig. 5, each shaft 12 is provided with gear teeth 58 which form a pinion in engagement with rack teeth 60 formed on a plunger 62 which is mounted for vertical movement in a bearing in the turret 8. A spring 64 serves to move the plunger 62 downwardly and to hold it normally in a 50 position determined by engagement of a collar 66 thereon with the top of the turret 8. With the parts in this position, the gripper is presented as shown in Fig. 2 so that the last and its upper are positioned bottom downward. At its lower end each of the plungers 62 is provided with a roll 68, and mounted in a fixed position adjacent to the turret 8 is a cam plate 70 (Fig. 1) which, by engagement 55 with the roll 68, raises the plunger 62 far enough to turn the work from the position

shown in Fig. 2 to that shown in Fig. 3. Each of the shoes in turn is thus inverted as the different work-presenting devices arrive in position to be acted upon by the cam 70. Preferably the cam 70 is long enough to hold 70 two or more of the shoes in inverted position at the same time, so that it is unnecessary to turn the turret 8 every time that it is desired to remove a shoe therefrom.

75 By reference to Fig. 4 it will be seen that there are provided by the construction hereinbefore described two pairs of co-operating gripper jaws 20 and 22 which are spaced apart laterally of the toe so as to engage the upper at what is commonly termed the corners of the toe, the jaws being so arranged that they point generally lengthwise of the last and the ends of the jaws being divergently inclined so that they are substantially tangential to the curve of the edge of the last 80 bottom and embrace the toe end of the last, thereby insuring that both pairs of jaws will maintain a firm grip upon the upper materials close to the edge of the last bottom. It will be evident that the pull is thus applied to the upper along its opposite side portions, instead of along its median line, so that the entire forepart of the upper is pulled 85 forwardly without danger of an undue excess of tension in any one location such as 90 might tend under some conditions to distort the lines of the upper. The effect of the forward pull on the upper is to draw it tightly about the heel end of the last and to take out the slack at the sides of the shank, which 95 contributes materially to the success of subsequent lasting operations on the shoe. By reference to Fig. 2 it will be seen that the upper is also pulled downwardly over the toe, and an important advantage in the use 100 of the gripper herein shown is that the upper is pulled down over the sides as well as over the end of the toe in such manner as to reveal to the workman the contour of substantially the entire toe end of the last. This is 105 110 of material assistance in determining whether the lines of the upper are in proper relation to the lines of the last. If any relative adjustment of the upper and the last is needed, this may be readily effected by swinging the heel end of the last to one side or the other, the opposite pairs of gripper jaws holding substantially the entire toe end of the upper 115 from shifting as the relative adjustment is effected.

120 In the use of the apparatus a workman, who may be of a less highly skilled and highly paid type than the operator of a lasting machine, stands in front of the table 10 and mounts the different uppers on their lasts, presenting each of the shoes to one of the upper-pulling devices and pulling the upper 125 forwardly on its last in the manner hereinbefore described. As the workman tips the last relatively to the gripper to pull the up- 130

per, he observes whether the lines of the upper are in proper relation to the contour of the lasts, and if necessary effects a relative adjustment between the last and the upper by swinging the heel end of the last to one side or the other while the gripper is holding the upper. Thereafter he applies the arm 38 to the shoe to hold it in position with the upper under tension. As he thus positions the shoes in the different work-presenting devices, the workman turns the turret 8, thereby carrying the shoes around into position for the operator of a lasting machine to receive them. As the different work-presenting devices arrive in position to be acted upon by the cam 70, the shoes are inverted to present them bottom upward as illustrated at the left-hand side of Fig. 1. After mounting several shoes on the turret the workman may turn his attention to such other duties as it may be advantageous for him to perform until such time as it is necessary for him again to position other shoes in the apparatus in order to keep the lasting machine operator continuously supplied with shoes.

Before removing a shoe from the apparatus the operator of the lasting machine grasps it in such manner as to hold the upper in its forwardly pulled condition and to prevent its displacement relatively to the last. On tennis shoe work, as herein shown, the shoe comes to the operator of the lasting machine with the heel end, as well as other parts of the upper, unfastened, and the operator will preferably place one hand about the heel end of the shoe to hold that end of the upper from displacement, and will place the other hand upon the toe end of the shoe, with his thumb resting upon the bottom of the toe end of the last and his fingers engaging the upper about the toe. By holding the shoe in this manner the operator may most readily transfer it and present it bottom upward to the lasting machine; and with the shoe presented to the operator bottom upward, as illustrated, it is in the most convenient position for him thus to grasp it. The shoe may be most conveniently removed from the gripper by pressing it downwardly so as to relieve the pressure on the arm 26 and thus permit the gripper to open, the lever 36 yielding against the resistance of its spring 40 to permit the shoe thus to be depressed.

While the invention has been described particularly by reference to its use to prepare the work for the operation of a lasting machine, it should be understood that the invention is not thus limited in its applicability, but may be advantageously utilized also in connection with other machines, such for example as pulling-over machines.

Having described the invention, what I claim as new and desire to secure by Letters 65 Patent of the United States is:

1. In apparatus of the class described, a device for pulling an upper forwardly on a last to prepare it for presentation to a pulling-over or a lasting machine, comprising upper-gripping means and a member about which the last may be tipped relatively to said upper-gripping means to render said means effective to pull the upper, said upper-gripping means and member being mounted for movement with the last and upper in a fixed path after the upper-pulling operation to present the work in a position more convenient for an operator to remove it.

2. In apparatus of the class described, a device for pulling an upper forwardly on a last to prepare it for presentation to a pulling-over or a lasting machine, comprising upper-gripping means and a member about which the last may be tipped relatively to said upper-gripping means to render said means effective to pull the upper, said upper-gripping means and member being mounted for turning movement with the last and upper after the upper-pulling operation from a position in which the last is bottom downward to a position in which it is bottom upward.

3. In apparatus of the class described, a device for pulling an upper forwardly on a last to prepare it for presentation to a pulling-over or a lasting machine, comprising upper-gripping means and a member about which the last may be tipped relatively to said upper-gripping means to render said means effective to pull the upper, said upper-gripping means and member being mounted for turning movement with the last and upper about an axis extending generally lengthwise of the last from a position in which the last is bottom downward to a position in which it is bottom upward, and means for effecting said turning movement.

4. In apparatus of the class described, a device for pulling an upper forwardly on a last to prepare it for presentation to a pulling-over or a lasting machine, comprising upper-gripping means and a member about which the last may be tipped relatively to said upper-gripping means to render said means effective to pull the upper, said upper-gripping means and member being mounted for turning movement with the last and upper to shift the position of the work after the upper-pulling operation, and rack and pinion mechanism for effecting said turning movement.

5. In apparatus of the class described, a device for pulling an upper forwardly on a last to prepare it for presentation to a pulling-over or a lasting machine, comprising upper-gripping means and a member about which the last may be tipped relatively to said upper-gripping means to render said means effective to pull the upper, said upper-gripping means and member being mounted for

turning movement with the last and upper from a position in which the last is bottom downward to a position in which it is bottom upward, spring means for holding the parts normally in a position in which the last is bottom downward, and mechanism for effecting said turning movement against the resistance of said spring means.

6. In apparatus of the class described, a toe gripper and a member about which a last may be tipped relatively to said gripper for pulling an upper on the last, said gripper and member being mounted for turning movement with the last and upper from a position in which the last is bottom downward to a position in which it is bottom upward.

7. In apparatus of the class described, a device for pulling an upper forwardly on a last to prepare it for presentation to a pulling-over or a lasting machine, comprising means constructed for use manually to grip the toe end only of the upper and to pull the upper forwardly and mounted for movement with the shoe from a position in which the last is bottom downward to a position in which it is bottom upward, said apparatus being constructed only to pull the upper and then to release the shoe with the upper at the toe in an unfastened condition.

8. In apparatus of the class described, a device for pulling an upper forwardly on a last to prepare it for presentation to a pulling-over or a lasting machine, comprising a gripper constructed for use manually to grip the toe end of the upper and to pull the upper forwardly, said device being constructed to release the shoe while it is held in the hands of the workman with the upper at the toe in an unfastened condition, and means for turning said upper-pulling device with the shoe after the upper-pulling operation to bring the shoe into a position more convenient for the workman to remove it.

9. In apparatus of the class described, an upper-pulling device comprising a gripper and a member operative in response to pressure of a last thereon to close the gripper on the toe end of an upper and about which the last may be tipped relatively to the gripper to cause the gripper to pull the upper, said upper-pulling device being mounted for movement with the last and upper from a position in which the last is bottom downward to a position in which it is bottom upward.

10. In apparatus of the class described, an upper-pulling device comprising upper-gripping means and a member about which a last may be tipped relatively to said upper-gripping means for pulling an upper on the last, and means for holding the last thus tipped to maintain the upper under tension, said upper-pulling device and holding means being mounted for movement to shift the position

of the work while the upper is under tension.

11. In apparatus of the class described, an upper-pulling device comprising a gripper and a member about which a last may be tipped relatively to the gripper while the gripper holds the toe end of an upper to pull the upper forwardly on the last, and means for holding the last thus tipped to maintain the upper under tension, said upper-pulling device and holding means being mounted for movement with the last and upper from a position in which the last is bottom downward to a position in which it is bottom upward.

12. In apparatus of the class described, an upper-pulling device comprising upper-gripping means and a member about which a last may be tipped relatively to said upper-gripping means to pull an upper on the last, and means for holding the last thus tipped to maintain the upper under tension.

13. In apparatus of the class described, an upper-pulling device comprising a gripper and a member about which a last may be tipped relatively to the gripper while the gripper holds the toe end of an upper to pull the upper forwardly on the last, and a device arranged to be applied to the upper and last to hold the last thus tipped with the upper under tension.

14. In apparatus of the class described, an upper-pulling device comprising a gripper and a member about which a last may be tipped relatively to the gripper while the gripper holds the toe end of an upper to pull the upper forwardly on the last, and a spring-controlled member arranged to be applied to the upper and last over the top of the last and to hold the last thus tipped to maintain the upper under tension.

15. In apparatus of the class described, an upper-pulling device comprising a gripper and a member about which a last may be tipped relatively to the gripper while the gripper holds the toe end of an upper to pull the upper forwardly on the last, an arm mounted for movements laterally of the last and heightwise of the last and having means for engaging the work at the rear of said member to hold the last tipped about said member with the upper under tension, and a spring acting on said arm to hold the last thus tipped.

16. An upper-pulling device, comprising means for gripping an upper at the toe end of a last and a member about which the last may be tipped relatively to the upper-gripping means to render said means effective to pull the upper forwardly on the last, said upper-gripping means being constructed to grip the upper in locations spaced apart laterally of the toe to render the forward pull on the upper effective along the sides of the last.

17. An upper-pulling device, comprising means for gripping an upper at the toe end

of a last and a member about which the last may be tipped relatively to the upper-gripping means to render said means effective to pull the upper forwardly on the last, said upper-gripping means comprising gripper jaws constructed and arranged to grip the upper in spaced locations substantially at the corners of the toe end of the last.

18. An upper-pulling device, comprising a toe gripper and a member about which a last may be tipped relatively to said gripper to render the gripper effective to pull an upper forwardly on the last, said gripper comprising different pairs of upper-gripping jaws spaced apart laterally of the toe and arranged to point in the general direction of the length of the last with their end faces divergently inclined to embrace the toe end of the last.

19. An upper-pulling device, comprising a toe gripper and a shoe rest member constructed to permit a last to be tipped relatively to said gripper for pulling an upper forwardly on the last and to permit the last also to be swung laterally to effect relative adjustment of the last and the toe end of the upper, said toe gripper comprising gripper jaws arranged to grip the upper in spaced locations substantially at the corners of the toe end of the last to hold the entire toe end of the upper from shifting in said relative adjustment of the last and the upper.

20. An upper-pulling device, comprising a toe gripper adapted for use manually to pull an upper forwardly on a last to prepare it for presentation to a pulling-over or a lasting machine, said gripper comprising different pairs of upper-gripping jaws spaced apart and arranged to grip the upper substantially at the corners of the toe end of the last.

21. In apparatus of the class described, a work-presenting device movable about a substantially vertical axis to transfer a last and its shoe materials bodily from one location to another location, said work-presenting device being mounted also for different movement to change the position of the work, and mechanism operative in the transferring movement of said device to impart thereto said different movement.

22. In apparatus of the class described, a work-presenting device constructed to receive and position a last and its shoe materials bottom downward, said work-presenting device being movable to transfer the work from one location to another location and differently movable also to present the work with the last bottom upward, and mechanism operative in response to the transferring movement of said device to cause it thus to present the work.

23. In apparatus of the class described, a work-presenting device movable about a substantially vertical axis to transfer a last and its shoe materials from one location to another location and mounted for movement also

about a different axis to change the position of the work, rack and pinion mechanism for effecting said last mentioned movement of the device, and a cam for operating said rack and pinion mechanism at a predetermined point in the transferring movement of the device.

24. In apparatus of the class described, a work-presenting device constructed to receive a last with an upper loosely assembled thereon and movable in a substantially horizontal plane to transfer the work bodily from one location to another location to present it to the operator of a pulling-over or a lasting machine, said work-presenting device being differently movable also to change the position of the work thereon and having means for holding the upper in assembled relation to the last.

25. In apparatus of the class described, a work-presenting device constructed to receive and position a last and its shoe materials bottom downward, said work-presenting device being movable about a substantially vertical axis to transfer the work bodily from one location to another location and differently movable also to present the work with the last bottom upward.

26. In apparatus of the class described, a rotatable turret having thereon devices for supporting a plurality of lasts and their shoe materials, said devices being arranged to receive and position the lasts bottom downward and mounted for turning movements about axes different from the axis of the turret to present the lasts bottom upward.

27. In apparatus of the class described, a rotatable turret having thereon devices for supporting a plurality of lasts and their shoe materials, said devices being mounted for turning movements to invert the lasts, and mechanism for operating said devices to invert different lasts in succession as the turret is rotated.

28. In apparatus of the class described, a device for pulling an upper on a last to prepare it for presentation to a pulling-over or a lasting machine, said device being mounted for movement about a substantially vertical axis from a position in which the pulling of the upper takes place to transfer the work with the upper under tension to the machine operator.

29. In apparatus of the class described, an upper-pulling device comprising upper-gripping means and a member about which a last may be tipped relatively to said upper-gripping means for pulling an upper on the last, said device being mounted for movement with the upper under tension from a work-receiving position into position to present the work to the operator of a shoe machine.

30. In apparatus of the class described, an upper-pulling device comprising a gripper and a member about which a last may be

- 5 tipped relatively to the gripper while the gripper holds the toe end of the upper to pull the upper forwardly on the last, and means for holding the last thus tipped to maintain the upper under tension, said upper-pulling device and holding means being movable from a work-receiving position into position to present the work to the operator of a shoe machine.
- 10 31. In apparatus of the class described, a rotatable turret, and devices carried by said turret for supporting a plurality of lasts with shoe uppers thereon and including grippers for pulling the uppers on their lasts and maintaining them under tension as the turret is turned to transfer the lasts and uppers from one location to another location. 70
- 20 32. In apparatus of the class described, a rotatable turret, a plurality of upper-pulling devices carried by said turret each comprising a gripper and a member about which a last may be tipped while the gripper holds the toe end of the upper to pull the upper forwardly on the last, and a spring-operated member associated with each gripper for holding the last thus tipped to maintain the upper under tension as the turret is turned to transfer the lasts and uppers from one location to another location. 75
- 30 33. In apparatus of the class described, a work-presenting device movable to transfer a last with an upper thereon from one location to another location and comprising means for pulling the upper on the last, said work-presenting device being differently movable also to change the position of the work after the upper has been pulled. 80
- 40 34. In apparatus of the class described, a work-presenting device movable about a substantially vertical axis to transfer a last with an upper thereon from one location to another location and comprising a gripper for pulling the upper forwardly on the last, said work-presenting device being movable also about a substantially horizontal axis to turn the work from a position in which the last is bottom downward to a position in which it is bottom upward. 85
- 50 35. In apparatus of the class described, a work-presenting device comprising a gripper for pulling an upper forwardly on a last and a member about which the last may be tipped relatively to the gripper to cause the gripper to pull the upper, said work-presenting device being movable to transfer the last and upper from one location to another location and mounted also for turning movement from a position in which the last is bottom downward to a position in which it is bottom upward. 90
- 60 36. In apparatus of the class described, a work-presenting device comprising a gripper for pulling an upper forwardly on a last, a member about which the last may be tipped relatively to the gripper to cause the gripper to pull the upper, and means for holding the last thus tipped, said work-presenting device being movable to transfer the last and upper with the upper held under tension from one location to another location and differently movable also to change the position of the last. 95
- 70 37. In apparatus of the class described, a work-presenting device movable to transfer a last with an upper thereon from one location to another location and comprising means for pulling the upper on the last, and mechanism operative in the transferring movement of said device to impart thereto a different movement to change the position of the work. 100
- 80 38. In apparatus of the class described, a work-presenting device comprising upper-gripping means and a member about which a last may be tipped relatively to said upper-gripping means for pulling an upper on the last, said work-presenting device being movable to transfer the work from one location to another location, and mechanism operative in the transferring movement of said device to turn said device from a position in which the last is bottom downward to a position in which it is bottom upward. 105
- 90 39. In apparatus of the class described, a rotatable turret having thereon a plurality of work-presenting devices each comprising a gripper, a member about which a last may be tipped relatively to said gripper for pulling an upper forwardly on the last and a member for holding the last thus tipped, each of said work-presenting devices being mounted for turning movement from a position in which the last is bottom downward to a position in which it is bottom upward, and mechanism operative in the rotation of the turret for thus turning said devices. 110
- 100 In testimony whereof I have signed my name to this specification.
